UNITED STATES PATENT OFFICE.

LIPA POLINKOWSKY, OF LONDON, ENGLAND, ASSIGNOR TO WESTERN ELECTRIC COMPANY, INCORPORATED, OF NEW YORK, N. Y., A CORPORATION OF NEW YORK.

MACHINE-SWITCHING TELEPHONE-EXCHANGE SYSTEM.

Application filed October 18, 1918. Serial No. 258,682.

To all whom it may concern:

Be it known that I, LIPA POLINKOWSKY, a citizen of Russia, residing at 70 Westbourne Terrace, Hyde Park, London, W., England, have invented certain new and useful Improvements in Machine-Switching Telephone-Exchange Systems, of which the following is a full, clear, concise, and exact description.

10 This invention relates to machine-switching telephone-exchange systems and more particularly to telephone-exchange systems of the semi-automatic type in which connections are extended over operators' positions, at which calls receive full supervision, the release of the call remains under the control of the operator, and the meter of the calling line is operated during the release of a successfully established connection. The object of this invention is the improvement of systems of the above character in which service is given to an area in which are also located satellites associated with the main exchange.

15 A feature of the invention is the provision of circuits and apparatus for extending calls over a satellite to the switches of an operator's position in an exchange, and for giving at the operator's position, the same full supervision, including control of release, etc., for the calls extended over the satellite, as for calls originating in the exchange.

In semi-automatic exchanges of the above character means are provided for holding a train of switches, used in extending a connection, in a predetermined condition, but freeing the terminals of both the calling and called subscriber's lines.

20 A further feature of the invention is the provision of means, associated with the switch in the satellite and the trunk line extending from the satellite to the exchange, for freeing the terminals of the calling subscriber's line and holding the switch, used in extending the call, in a predetermined condition, when the switches in the exchange are brought into a holdover condition.

25 Another feature of the invention is the provision of means associated with the switch of the satellite, for extending a call, initiated in the satellite, to the switches in the exchange, independent of the subsequent

condition of the subscriber's line initiating such call, and means, located in the satellite 55 and operating in response to a condition created over the switches of the exchange to which such call has been extended, removing in the satellite the calling condition so as to cause the transfer over the satellite of the 60 condition of the calling line to the supervisory means at the switches of the exchange.

In the drawings:

Figure 1 shows a subscriber's line and a 65 first line finder in a satellite.

Figure 2 shows a trunk line for calls outgoing from the satellite to the exchange. This figure also shows a local subscriber's line terminating in the finder at the exchange.

Figure 3 shows a cord consisting of a second line finder, and a first group selector in the exchange.

Figure 4 shows the searching sequence 75 switch of the cord and an operator's position indicated as far as is essential for the understanding of the system.

The system disclosed as embodied in the present invention will be best understood 80 from a description of the operation thereof.

When the receiver is removed on a subscriber station and line relay 101 is energized over the subscriber line, a circuit is closed over front contact of relay 101 for 85 the energization of the common starting relays 104 of the line finder group including the individual resistance 102 and 103, and both windings of each common starting relay. A potential is thereby created on terminal 110. The power magnet 111 of each free first line finder in the group is energized in a circuit including contact 116 bottom of sequence switch 120 individual to the line finder, back contact of test relay 90 112, contact 117 top of sequence switch 120 and front contacts of relays 104. When the line finder reaches the terminals of the calling line the righthand winding of test relay 114 is energized in a circuit over terminal 110, relay 114 brings over its front contact its lefthand low resistance winding in parallel to its righthand high resistance winding and on terminal 110 is created a busy potential. When the brush carriage is 105 centered and its contact 119 is opened, the

short-circuiting around winding of relay 112 is removed and this relay is energized, disconnecting on its back contact power magnet 111 and connecting over its front contact 5 a circuit for the energization of sequence switch 120 including its contact 122 top. In parallel to the sequence switch 120 is also connected over its contact 124, bottom, the holding magnet 115 of the line finder, the 10 brush carriage is arrested, whereas sequence switch 120 starts from position 1 and under the control of its local contact 121 moves into position 5. In position 3 of sequence switch 120 a circuit is established for the 15 energization of the cut-off relay 107 over terminal 118, lefthand back contact of relay 113 and sequence switch contact 123, bottom. Relay 107 disconnects relay 101 and this in turn causes the de-energization 20 of relays 104 and 114; also the power magnets of the remaining free first line finders are de-energized and these line finders are arrested. The magnet of the message register 108 is also included in parallel with 25 cut-off relay 107 but does not receive sufficient current to operate at this time. As soon as relay 114 is de-energized, relay 127 is energized in a circuit over sequence switch contact 116, top, righthand back contact of 30 relay 113, back contact of relay 114 and winding of relay 112. In position 4 of sequence switch 120 the lefthand windings of repeating coil 129 and the supervisory relay 131 are connected with the subscriber's line 35 over sequence switch contacts 125 and 126, bottom, and both front contacts of relay 127. Relay 131 is thereby energized. In position 40 5 of sequence switch 120 the righthand winding of relay 137 is connected in bridge to the trunk line 140 over sequence switch contacts 128 bottom and 130 bottom. The winding of relay 151 in the exchange being 45 of high resistance hinders the energization of relay 137. Relay 151 provides over its front contact a circuit for the energization 50 of the common starting relays 154 including the individual resistance 152 and 153. Over resistance 155 and righthand back contact of cut-off relay 156 a potential is created on terminal 230. A second line finder in the 55 exchange, as shown in Figure 2, then obtains a connection with the calling trunk line 140 which leads from the satellite shown in Fig. 1 to the terminal bank of the second line finder switch at the central exchange and the call is extended to an operator's position.

The start relays 154, on energizing, complete a circuit from ground over their armatures and contacts, conductor 105, contact 60 312, contact 211, bottom, winding of relay 252 to battery. Relay 252 energizes and closes a circuit from ground through its armature and front contact, armature and back contact of relay 262, contact 212, top, 65 winding of the power magnet 261 to battery.

Power magnet 261 causes the brush carriage of the line finder switch to rotate to search for the calling trunk line. When the test brush 201 encounters the test terminal 230 of the calling trunk 140, a circuit is closed 70 from battery through the inner windings of relays 154, resistance 152, contact and armature or relay 151, resistance 155, back contact and right-hand armature of relay 156, terminal 230, brush 201, contact 215, bottom, right-hand high resistance winding of relay 264, contact 301, contact 202, bottom, to ground. Test relay 264 operates and completes a circuit through its left-hand low 75 resistance winding and contact and armature and the winding of relay 262 to ground in shunt of the right-hand high resistance winding. When the brushes of the line finder are accurately centered, the contact 203 is opened and relay 262 operates to open 80 the circuit of the power magnet 261, causing the line finder switch to come to rest in engagement with the terminals of the calling trunk line. The low resistance right-hand winding of relay 264 reduces the potential 85 on terminal 230 and its multiples to render the trunk non-selectable to other switches. Relay 262 also closes a circuit from battery through the winding of sequence switch magnet 250, contact 204, bottom, front contact and armature of relay 262, front contact 90 and armature of relay 252 to ground. Sequence switch 250 advances out of position 1. 95

On leaving position 1 sequence switch 250 opens the original energizing circuit of relay 252, but this relay is again energized in the following circuit as soon as the sequence switch reaches position 2; battery, through the winding of relay 252, contact 217, top, contact 205, bottom, of sequence switch 220, back contact and armature of relay 242 to ground. As sequence switch 250 passes through position 2½, a circuit is completed from battery through the winding of sequence switch magnet 220, contact 206, bottom, contact 218, bottom, back contact and left-hand armature of relay 263, contact 210, top, to ground. Sequence switch 220 energizes in this circuit and moves out of position 1 and into position 4. Immediately 100 that sequence switch 250 reaches position 2 a circuit is established from battery through the right-hand winding of relay 157, terminal 207, brush 208, winding of relay 227, back contact and left-hand armature of relay 225, normal contact of relay 224, contact 216, top, to ground. It will be noted that relays 158 and 159 are included in parallel with this circuit, but the current flowing is insufficient 105 to cause their operation. Relay 157, however, attracts its armature and closes a circuit for the cut-off relay 156. Relay 156 opens the circuit for relay 151 which removes battery potential from terminal 230 and also permits the deenergization of the 110 115 120 125 130

- start relays 154 to disconnect ground from the common start conductor 105, causing all other line finder switches to cease hunting. Relay 156, by removing the potential from the test terminal 230, opens the energizing circuit of relays 264 and 262. Relay 262 thereupon deenergizes and opens the driving circuit of sequence switch 250 in order that said sequence switch will stop in position 4.
- 10 At the time relay 157 operates the relay 227 is energized in a circuit therewith and also attracts its armatures. Relay 227 establishes a circuit from battery through the lower left-hand winding of repeating coil 229, supervisory relay 231, contact 232, top, right-hand armature and front contact of relay 227, thence over the lower side of the trunk 140, contact 128, bottom, right-hand winding of relay 137, contact 130, bottom, over the upper side of the trunk 140, front contact and left-hand armature of relay 227, contact 209, top, upper left-hand winding of repeating coil 229 to ground. A flow of current in this circuit is sufficient to operate the marginal relay 137 in the satellite office. Relay 137, on energizing, completes a circuit from battery through the winding of sequence switch magnet 120, contact 131', bottom, front contact and armature of relay 137 to ground. Sequence switch 120 becomes energized in this circuit and moves out of position 5 and into position 9. The supervisory relay 231 is also energized in series with the relay 137 and remains energized in position 6 of sequence switch 120 over a temporary circuit closed at the top of contact 133. Before this temporary circuit is opened to permit the deenergization of relay 231, contacts 130 and 128, top, are closed to extend the conductors of the trunk 140 through the right-hand windings of repeating coil 129 to the windings of relay 132. Since the calling subscriber's receiver is off the switch hook at this time, the supervisory relay 131 is energized and at its armature and contact shunts out the left-hand high resistance winding of relay 122 so that only the low resistance right-hand winding thereof is included in series with the trunk 140 and the supervisory relay 231. The resistance of this circuit being low, relay 231 remains energized and holds open the circuit of the supervisory lamp 245. At the instant the sequence switch 120 passes into position 6, relay 132 operates, as explained, and at its armature and contact closes a shunt around the winding of relay 112. Relay 112 thereupon deenergizes prior to the arrival of sequence switch 120 in position 9.
- 15 In position 4 of sequence switch 220 a circuit is closed from battery through the winding of relay 308, lamp 270, contact 218, top, back contact and left-hand armature of relay 263, contact 210, top, to ground. Lamp 270 is illuminated and relay 308 is energized to close a lighting circuit for lamp 372. The illumination of these lamps apprises the operator that a call is awaiting her attention.
- 20 In position 4 of sequence switch 250 the sender searching sequence switch 330 is operated to associate the cord circuit, illustrated in Fig. 3, with an idle register sender mechanism. The circuit for sequence switch 330 may be traced from battery through the windings of relay 313, winding of sequence switch magnet 330, contact 219, bottom, back contact and armature of relay 262, front contact and armature of relay 252 to ground. The sequence switch 330 commences to rotate and as soon as an idle register sender is found a test circuit is completed from battery through the contact and left-hand armature of relay 314, contact 315, contact 316, right-hand winding of relay 305, contact 303, contact 222, bottom, right-hand winding of relay 264, contact 302, bottom, of sequence switch 330 to ground. Due to the presence of selectable potential at the contact 306 corresponding to the idle register sender, illustrated at the lower right-hand part of Fig. 4, the relay 264 receives sufficient current through its high resistance winding to operate. Relay 264 immediately completes a circuit through its left-hand low resistance winding and the winding of relay 262 in shunt of its high resistance winding, thereby reducing the potential on terminal 306 to render the selected register sender busy to other searching sequence switches. Relay 262 operates and opens the circuit of sequence switch 330 causing the same to stop and also completes a circuit from battery through the winding of sequence switch magnet 250, contact 204, bottom, front contact and armature of relay 262, front contact and armature of relay 252 to ground. Sequence switch 250 leaves position 4, moves over position 5 and into position 8. In leaving position 5 the circuit of relay 252 is opened and this relay becomes deenergized. Also as sequence switch 250 leaves position 5 it opens contact 222, bottom, and permits the deenergization of relays 264 and 262. Sequence switch 250, upon passing position 6, closes a circuit from battery through the winding of sequence switch 220, contact 223, bottom, contact 226, top, back contact and right-hand armature of relay 225 to ground. The momentary closure of this circuit causes the energization of sequence switch 220 which advances out of position 4 and into position 5. The lamps 270 and 372 are now caused to flash by the interrupter 236 which is included in a circuit traceable over contact 228, bottom, lamp 270, relay 308 to ground. It will be noted that the original circuit for the steady illumination of these lamps is opened at contact 218, top, when sequence switch 250 leaves position 6. The flashing of the lamps 270 and 372 indicates

to the operator that an idle register controlling mechanism has been seized and is ready to receive the record of the called subscriber's line.

5 In position 5 of sequence switch 220 the operator's telephone set, shown in Fig. 4, is connected in operable relation to the calling subscriber's line at contacts 209 and 232, bottom. The operator converses with the 10 calling subscriber and ascertains the designation of the desired line. She thereupon proceeds to set up the record of the called line on a keyboard at her position which serves to position registers, which, in turn, 15 operate to control the selective movement of group selector switches to extend the incoming trunk 140 through to the called subscriber's line. The operator's keyboard, the registers and the various other elements 20 of the register controlling mechanism have been omitted from the disclosure for the sake of simplicity. Controlling mechanisms of this general character are, however, numerous and well-known in the art, and since 25 the register sender plays no important part in the subject matter of the present invention, it has not been shown in full. The register sender mechanism, among other elements, is provided with a sequence switch 30, which, in the usual manner, advances 30 from position to position during the progress of setting up the connection on the registers and during the progress of controlling the several selective switches to 35 bring about the necessary circuit changes for this purpose.

Referring to the elements of the sender which have been shown in the drawing, it 40 will be recalled that the relay 305 was included in the test circuit with relay 264 and relay 262 at the time the register sender was selected by the searching sequence switch 330. Relay 305 operates and closes 45 a circuit from battery through its left-hand winding and contact and left-hand armature, contact 317, right-hand winding of relay 305, and thence over the conductor 318 to ground. Relay 305, on operating, closes a circuit from battery through 50 the winding of sequence switch magnet 310, contact 319, lower, front contact and right-hand armature of relay 305 to ground driving said sequence switch out of position 1 and into position 5. After the number has 55 been set up on the operator's keyboard a circuit is closed in any well-known manner for advancing the sequence switch 310 into position 7. In this position of sequence switch 310 a circuit is completed from battery through the winding of sequence switch 60 220, contact 214, bottom, contact 303, contact 304, front contact and right-hand armature of relay 305 to ground. Sequence 65 switch 220 moves out of position 5 and into position 8 and in so doing disconnects the

operator's telephone set from talking relation with the subscriber's line. In position 8 of sequence switch 220 a circuit is closed from battery through lamp 340, contact 238, interrupter 236 to ground, whereby the lamp 70 340 is intermittently illuminated.

When the register sender is completely prepared to control selection its sequence switch 310 will have advanced into some position, such as position 10, and the fundamental circuit is established. This circuit may be traced from battery through the winding of relay 252, contact 217, bottom, contact 309, armature and contact of relay 307, stepping relay 324, contact 320, bottom, 75 to ground. Relay 252 operates and closes a circuit from battery through the winding of sequence switch magnet 250, contact 233, bottom, the back contact and armature of relay 262, front contact and armature 80 of relay 252 to ground, driving sequence switch 250 into position 9. Brush selection now takes place at the first group selector switch and for this purpose a circuit is closed from battery through the magnet of 85 the trip spindle 273, contact 221, bottom, front contact and armature of relay 252 to ground. The trip spindle is rotated and for each brush tripping position a circuit is closed from battery through the winding of relay 252, contact 211, top, to ground 90 at the interrupter contacts 275. This circuit causes the shunt of the stepping relay 324 in the well-known manner, which, in turn, causes the advance of the register, not shown. When the proper set of brushes has been reached the fundamental circuit is opened at the sender and relay 252 becomes deenergized as soon as the interrupter contacts 275 are opened thereafter. Relay 95 252 severs the circuit of the trip spindle magnet and completes a circuit from ground through its armature and back contact, contact 204, top, winding of sequence switch magnet 250 to battery. Sequence switch 100 250 leaves position 9 and as soon as it reaches position 10 relay 252 is again energized over a circuit including contact 217, top, contact 214, top, of sequence switch 220, contact 303, contact 304, front contact and 105 right-hand armature of relay 305 to ground. Relay 252 attracts its armature and opens the circuit of sequence switch magnet 250, 110 whereby said sequence switch comes to rest in position 10.

The brush carriage of the group selector is rotated to advance the tripped set of brushes over the terminals of the bank to search for an idle trunk. For this purpose 115 a circuit is closed from battery through the winding of the brush carriage power magnet 281, contact 212, bottom, back contact and armature of relay 262, front contact and armature of relay 252 to ground. When the brush 120 276 encounters the test terminal of 125 130

the first idle trunk, a selectable potential existing thereon, a circuit is closed over said brush, contact 215, top, right-hand high resistance winding of relay 264, contact 226, bottom, back contact and right-hand armature of relay 225 to ground. Relay 264 operates and closes a circuit through its low resistance left-hand winding and the winding of relay 262 to ground. Relay 262 attracts its armature and opens the circuit of the power magnet 281, whereby the brush carriage ceases to rotate. Relay 262 also closes a circuit from battery through the winding of sequence switch magnet 250, contact 204, bottom, front contact and armature of relay 262, front contact and armature of relay 252 to ground, driving sequence switch 250 over position 11 and into position 12.

The fundamental circuit is now extended over contacts 309 and 311 and contacts 237 and 238 to the next succeeding selector switch in the train. In the well-known manner the register controlling mechanism causes the selective movement of the succeeding switches and the connection is extended through to the called subscriber's line.

Following the last selective movement of the final switch, the controlling switch 310 of the register mechanism, having advanced to a position where the circuit of relays 305 is opened, this relay becomes deenergized and opens the circuit of relay 252. Relay 252 releases its armature and closes a circuit from battery through the winding of sequence switch 250, contact 204, top, back contact and armature of relay 252 to ground. Sequence switch 250 moves out of position 12 and into position 14. During the operation of the final switch, not shown in this disclosure, the controlling sequence switch thereof, in passing from one position to another following the completion of selection, closes a temporary short-circuit across the line conductors, which completes a circuit for supervisory relay 242 including the right-hand windings of repeating coil 229. Relay 242 attracts its armature and closes a circuit including the contact 206, top, for driving sequence switch 220 out of position 8 and into position 9. When, an instant later, the short-circuit across the line is opened at the final switch relay 242 becomes deenergized and a circuit is closed from ground through the armature and back contact of said relay, contact 223, top, winding of sequence switch magnet 222. Sequence switch 220 leaves position 9 and moves into position 11. The manner in which the short-circuit is temporarily established across the line conductors at the final selector switch is illustrated and described in applicant's Patent, No. 1,193,053, issued August 1, 1916. In position 11 of sequence switch 220, a circuit is closed from battery through the lamp

240, contact 205, top, back contact and armature of relay 242 to ground. The illumination of lamp 240 notifies the operator of the fact that the called line has been selected and ringing current is being applied thereto. 70

The response of the called subscriber results in the closure of the line-circuit in series with the right-hand windings of repeating coil 229 and the consequent energization of relay 242. The circuit is then closed including contact 206, top, for advancing sequence switch 220 into position 14. The lamp 240 is extinguished, notifying the operator that the called subscriber has answered. 80

At the completion of conversation both the calling and called subscribers replace their receivers on the switch hooks. The opening of the calling line causes the deenergization of relay 131 in the satellite office. This relay at its armature and contact removes the shunt around the high resistance winding of relay 132. The high resistance of relay 132 being included in series with relay 231, the flow of current is so diminished that relay 231 releases its armature. A circuit is, therefore, established from battery through the lamp 245, contact 213 to ground at the armature and contact of relay 213. The opening of the called subscriber's line permits the deenergization of relay 242 which completes a circuit from battery through lamp 235, contact 234, top, back contact and armature of relay 242 to ground. The operator, observing the illumination of both lamps 245 and 235, is aware that the subscribers have replaced their receivers on the switch hooks and that the connection is no longer required. She then proceeds to release by actuating the key 280. 100

Upon the actuation of key 280 a circuit is closed from battery through the left-hand winding of release relay 263, contact of key 280, contact 213, contact and armature of relay 231 to ground. Relay 263 operates and locks in a circuit from battery through its right-hand winding, front contact and right-hand armature, contact 202, top, to ground. Relay 263 closes a circuit from battery through the winding of sequence switch magnet 250, front contact and left-hand armature of relay 263, contact 210, top, to ground. Sequence switch 250 leaves position 14. When sequence switch 250 reaches position 15 a circuit is closed from battery through the winding of sequence switch magnet 220, contact 223, bottom, contact 226, top, back contact and right-hand armature of relay 225 to ground. Sequence switch 220 leaves position 14 and commences to rotate into its normal position 1. While sequence switch 220 is passing from position 16 to position 18 a circuit is closed from the source of metering current 359, key 364, contact 316, bottom, normal contacts of relay 224, left- 125

hand armature and back contact of relay 225, winding of relay 227, and thence in parallel to the right-hand winding of relay 157 and the windings of relays 158 and 159. 5 The source 359 increases the flow of current in the circuit traced to an extent sufficient to cause the operation of relays 158 and 159. Relays 158 and 159 connect the opposite poles of batteries 161 and 162 to 10 the two sides of the trunk 140 leading back to the satellite office.

At the time sequence switch 220 leaves position 14 on its way to normal, contact 232 is opened and consequently the relay 132 15 becomes deenergized. Relay 132 removes the shunt from around the winding of relay 112 and this relay again operates in series with relay 127. Relay 112 completes a circuit from ground through the contact 117, 20 bottom, armature and front contact of relay 112, contact 122, top, winding of sequence switch magnet 120 to battery, driving said sequence switch out of position 9 into position 17. As sequence switch 120 reaches 25 position 10, the trunk conductors 140 are connected by way of contacts 130 and 133 to the right-hand winding of marginal relay 137. The current flowing from the source 161, 162 is sufficient to cause the 30 operation of the marginal relay 137 which attracts its armature and locks in a circuit through its left-hand winding and contact 131, top. The function of this relay is, as will be later explained, to permit or to 35 hinder, as the case may be, the application of metering current to the calling subscriber's line at the time of disconnection. In the present instance, since the call was 40 successful, the calling subscriber's meter 108 will be operated in the manner about to be explained. As the sequence switch 120 reaches position 14 and from there on through position 16, a circuit is closed from the metering source 123', contact 123, top, left- 45 hand armature and back contact of relay 113, contact 118, winding of magnet of meter 108 to battery. Current flowing in this circuit is sufficient to cause the operation of the meter magnet and the call is recorded 50 against the subscriber's line. In position 17 of sequence switch 120 a circuit is established from battery through the winding of the holding magnet 115, contact 124, top, lower right-hand winding of repeating coil 129, 55 the windings of relay 132, upper right-hand winding of said repeating coil contact 130, top, over the upper side of the trunk 140, back contact and left-hand armature of relay 157 to ground. It will be noted that 60 relay 157 has, in the meantime, become deenergized following the opening of the contact 116, bottom, as sequence switch 220 leaves position 18. Relay 132, therefore, becomes energized and reestablishes the shunt 65 around the winding of relay 112. Relay 112

becomes deenergized and a circuit is closed from ground through the contact of relay 117, bottom, armature and back contact of relay 112, contact 122, bottom, winding of sequence switch magnet 120 to battery. 70 Sequence switch 120 moves out of position 17 and into its normal position, position 1.

Sequence switch 250, which left position 14 at the time the operator manipulated the disconnect key 280, moves into position 17 75 where it comes to rest. As soon thereafter as sequence switch 220 arrives in position 1 a circuit is closed from battery through the winding of relay 252, contact 217, top, contact 205, bottom, back contact and armature of relay 242 to ground. Relay 252 operates and closes a circuit from battery through the winding of sequence switch magnet 250, contact 233, bottom, back contact and armature of relay 162, front contact and armature of relay 252 to ground, driving sequence switch 250 into position 18. On leaving position 16 the circuit of test relays 264 and 262 is opened which may serve in any well-known manner to cause the release 80 of the succeeding switches. In position 18 of sequence switch 250 a circuit is closed from battery through the winding of the brush carriage power magnet 281, contact 212, bottom, and thence to ground at the 85 contact and armature of relay 252. The brush carriage rotates and upon reaching its normal position a circuit is closed from battery through the winding of holding magnet 285, contact 241, top, brush 289 and 90 its home contact, winding of relay 262 to ground. Relay 262 opens the circuit of the power magnet 281 and closes a circuit from battery through the winding of sequence switch magnet 250, contact 204, bottom, 95 front contact and armature of relay 262, front contact and armature of relay 252 to ground. The sequence switch thereupon moves into its normal position and relays 252, 262 and 263 become released. 100 Should the called subscriber's line be busy at the time connection is extended thereto, the relay 242 is held permanently energized by means of the short-circuit above referred to across the talking conductors at the final 105 switch. Consequently, the sequence switch 220 advances out of position 8 upon the energization of relay 242, and remains in position 9 instead of moving immediately 110 therefrom, as in the case of the line being idle. With sequence switch 220 in position 9 the busy tone coil 247 is connected to the talking conductors and transmits a tone over the line to notify the calling subscriber that the desired line is busy. Moreover, the lamp 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 switch hook, which opens the circuit of relay 131 and permits the inclusion of the high resistance winding of relay 132 in series with the relay 231. Relay 231 energizes and causes the illumination of the supervisory lamp 235.

The operator then initiates release by depressing disconnect key 280. It is to be observed that the distinction between release after a successful connection and release following the attempt of a connection to a busy line is that in the latter case the sequence switch 220 is only advanced as far as position 9. When, therefore, sequence switch 250 leaves position 14 and moves through position 15, it does not close a circuit for sequence switch 220, as before, at the contact 226, top, inasmuch as this circuit is now held opened at contact 223, bottom. Consequently, sequence switch 220 remains in position 9 while sequence switch 250 continues to advance on into position 17. Immediately that sequence switch 250 leaves position 16, contact 210, top, is opened and relays 227 and 157 become deenergized. Relay 227 closes a circuit from battery through the right-hand winding of relay 224, back contact and left-hand armature of relay 227, contact 209, top, upper left-hand winding of repeating coil 229 to ground. Relay 224 operates and locks in a circuit from battery through its left-hand armature and front contact and left-hand winding to ground. When sequence switch 250 leaves position 16, the test circuit leading over brush 276 to the succeeding switches is opened and these switches release in the well-known manner. Finally the deenergization of relay 242, which also occurs at the time contacts 237 and 238, top, are opened, the sequence switch 220 is driven out of position 9 and into position 11. In position 11 a circuit is closed from battery through the winding of sequence switch magnet 220, contact 223, bottom, contact 226, top, back contact and right-hand armature of relay 225 to ground. Sequence switch 220 leaves position 11 and moves through position 14 and into position 1. This time, however, the normal contacts at the right-hand armature of relay 224, are opened as sequence switch 220 passes through position 16 to position 18, and, consequently, the metering battery 359 is not connected to the windings of relays 158 and 159. Hence, the relay 137 in the satellite office remains inert during the time that sequence switch 220 is advancing through positions 10 to 13. As a result a circuit is closed from battery through the left-hand winding of relay 113, contact 135, bottom, back contact and armature of relay 137 to ground. Relay 113 operates, opens the circuit of relay 127 and closes a circuit from battery through contact 116, top, right-hand wind-

ing and front contact and right-hand armature of relay 113, back contact and armature of relay 114, the winding of relay 112 to ground. Relay 113 being energized at the time sequence switch 120 moves to positions 14 and 16, the circuit for the application of the metering source 123' is opened, and, consequently, the meter 108 is not operated to charge the call against the subscriber's line. In position 17 of sequence switch 120, relay 132 is operated, as above explained, and the sequence switch 120 is advanced into its normal position, position 1. Furthermore, release of the switch at the exchange takes place in the manner already explained.

In the lower part of Fig. 2 a local subscriber's line, terminating in the central office, is shown. As illustrated, this line terminates directly in the multiples of the line finder switch shown in Fig. 3. It will be understood, of course, that a primary line finder, similar to the one shown in Fig. 1 of the satellite, may be installed whereby the local subscriber's line is first extended over the primary switch and thence to the terminal bank of the secondary line finder shown in Fig. 3. In either case, the second line finder has access both to subscribers' lines terminating locally in the exchange and also incoming trunk lines from distant satellite offices. When a local subscriber, such, for example, as the subscriber of line 141, initiates a call, the line relay 142 is operated and start relays, similar to relay 154, are energized to initiate the movement of the second line finder switches having access to said line. When the brushes 201, 208, etc. of the line finder have seized the terminals of the local subscriber's line, cut-off relay 143 is operated in the manner explained, and when at the end of a successfully established connection release occurs, the source of metering current 359 is connected over the brush 208, precisely in the manner explained above in detail, to the windings of the cut-off relay 143 and the message register magnet 144. Thus, the call is charged against the calling subscriber.

By such an arrangement the function of the cord circuit and the apparatus at the operator's position is always the same regardless of the nature of the incoming line, that is whether the calling line is one terminating locally in the central office or one which has been extended thereto over a two-wire interoffice trunk line. In the case of a local line, metering current is applied directly to the subscriber's meter individual to the line, whereas in the case of a call from a distant satellite office, metering current is connected to the two-wire trunk and in turn causes the application of current over the conductors of said trunk leading

back to the satellite office and there controls apparatus to cause the operation of the register individual to the calling line.

Should the operator in the central office desire for any reason to hold the switches of an established connection in their operated condition and at the same time to free the calling subscriber's line in the satellite office, she may do so by depressing the key 239 in conjunction with the key 365. The actuation of these keys completes a circuit from battery traceable through the right-hand winding of relay 225 to ground. Relay 225 operates and opens the circuit of relay 227. Relay 227 releases and opens the circuit of relay 132 which becomes deenergized and removes the shunt from around the winding of relay 112. Relay 112 becomes energized and closes the above traced circuit for driving sequence switch 120 out of position 9 and into position 17. Since sequence switch 220 remains in position 14 the meter battery 359 is not connected to the relays 158 and 159 and hence relay 137 in the satellite remains deenergized. Consequently, relay 113 operates as sequence switch 120 passes position 13 and locks to prevent the application of metering battery 123' to the calling subscriber's message register.

At the time relay 227 deenergizes the circuit of relay 157 is also opened but relay 157, being slow to release in character, maintains its armature attracted until relay 227 has had time to completely retract its armature. A new circuit for relay 157 is then established from ground through the left-hand winding of said relay, front contact and right-hand armature of relay 156, terminal 230, brush 201, back contact and right-hand armature of relay 227, contact 232, top, winding of relay 231, the lower left-hand winding of repeating coil 229 to battery. Relay 157 remains energized and holds the circuit previously traced through the holding magnet 115 and the windings of relay 132 open at the time sequence switch 120 moves in position 17. Therefore, the sequence switch 120 is held in position 17 and the first line finder switch is maintained in its partially released condition so long as the connection is held at the central office. The calling subscriber's line, however, is rendered free. The cut-off relay 107 is deenergized after sequence switch 120 leaves position 13 and the calling subscriber's line is rendered free to initiate other calls. When the operator decides to release the connection she may do so by depressing the release key 280 and release follows in the manner previously described.

Another feature of the system herein disclosed is the arrangement wherein a call,

once initiated in a satellite office, is extended through to the operator's position, uninterrupted, notwithstanding the fact that the calling subscriber may abandon the call after having initiated the movement of the first line finder switch. Once the line finder has found the calling subscriber's line sequence switch 120 moves into position 5, as above described. Shortly thereafter the relay 132 is operated to shunt the relay 112 which completes a circuit for advancing the sequence switch 110 out of position 5 and into position 9. If the calling subscriber has abandoned the call, relay 131 becomes deenergized and removes the shunt around the high resistance winding 132. Consequently, relay 231 at the distant office becomes deenergized. The second line finder in the central office having operated in response to the actuation of relay 151 to find the trunk 140, sequence switch 250 is moved out of position 1 and into position 4. Consequently, with the sequence switch 220 in position 4 and relay 131 deenergized, relay 231, as explained, is unable to maintain its armature attracted due to the high resistance of the left-hand winding of relay 132. A circuit is, therefore, closed from battery through the lamp 245, contact 213, armature and contact of relay 231 to ground. The operator seeing the lamp 245 illuminated knows the calling subscriber has prematurely abandoned the call and she proceeds to bring about the release of the connection by depressing the key 280.

What is claimed is:—

1. A telephone exchange system comprising a main exchange and satellite exchanges, calling lines terminating at said exchanges, an operator's position in said main exchange, trunk lines between said main exchange and said satellite exchanges, automatic means at said satellite exchanges for extending a calling line over one of said trunk lines from one of said satellite exchanges to said operator's position in said main exchange, controlling means at said operator's position, and means responsive to the operation of said controlling means for holding an automatic switch in a satellite exchange in the connection as established while the calling line is rendered free to call and to be called.

2. A telephone exchange system comprising a line, an automatic switch, means for operating the automatic switch to extend said line, means controlled by said switch in its operated condition for rendering the line busy, means for rendering the line continually idle during the rest of the period said switch remains in its operated condition, and means for releasing said switch.

3. A telephone exchange system comprising a line, an automatic switch, terminals for the line in said switch, means for oper-

ating said switch into engagement with said terminals to extend said line, means controlled by said switch in its operated condition for rendering the line busy, means for rendering the line continually idle during the rest of the period said switch remains in engagement with the terminals thereof, and means for releasing said switch.

4. A telephone exchange system comprising a line, an automatic switch, a trunk, means for operating the automatic switch to extend said line over said trunk, means controlled by said switch in its operated position for rendering the line busy, means controlled over said trunk for rendering the line continually idle during the rest of the period said switch remains in its operated condition, and means for releasing said switch.

5. A telephone exchange system comprising a line, an operator's position, an automatic switch, means for operating said switch to extend said line to the operator's position, selective switches for further extending said line, means controlled by said automatic switch in its operated condition for rendering said line busy, means controlled by the operator for rendering the line idle while said switches are held in their operated condition, and means controlled by

the operator for releasing said switches.

6. A telephone exchange system comprising a line, a plurality of automatic switches, means responsive to a certain condition on said line for operating said switches in succession to extend said line, and means for releasing said switches, said switches arranged to continue in operation once their operation is initiated to extend said line regardless of the subsequent condition that may exist on said line.

7. A telephone exchange system comprising a line, an operator's position, a plurality of automatic switches, means responsive to a calling condition on said line for operating said switches in succession to extend such line to the operator's position, a signal at said position, means for operating said signal when the calling condition is removed from said line, and means controlled by the operator for releasing the switches, said switches being arranged to continue in operation once their operation is initiated to extend the line to the operator's position regardless of whether the calling condition on said line is maintained or is immediately removed.

In witness whereof, I hereunto subscribe my name this 16th day of August, A. D., 1918.

LIPA POLINKOWSKY.
